UNITED STATES PATENT OFFICE.

ANDREW EPPLER, OF LYNN, MASSACHUSETTS, ASSIGNOR TO UNITED SHOE MACHINERY COMPANY, OF PATERSON, NEW JERSEY, A CORPORATION OF NEW JERSEY.

THREAD-WAXING DEVICE.

1,091,126.

Specification of Letters Patent. Patented Mar. 24, 1914.

Application filed August 19, 1912. Serial No. 715,799.

To all whom it may concern:

Be it known that I, ANDREW EPPLER, a citizen of the United States, residing at Lynn, in the county of Essex and State of Massachusetts, have invented certain new and useful Improvements in Thread-Waxing Devices; and I do hereby declare the following to be a full, clear, and exact description of the invention, such as will enable others skilled in the art to which it appertains to make and use the same.

The present invention relates to wax thread shoe sewing machines, and more particularly to thread waxing devices for such machines.

The invention is designed primarily as an improvement in thread waxing devices of the type which comprise a receptacle for the wax, a heating device extending into the receptacle and surrounded by the wax contained therein, and devices for guiding the thread into and out of the receptacle.

In thread waxing devices of this character it frequently happens that the heat transmitted by the heating device is not sufficient to melt the wax thoroughly at the point where the thread passes through the receptacle, and that the wax therefore does not permeate the thread, but the thread receives merely a surface coating of wax in the waxing device. Also the heat of the heating device is often not sufficient to melt the wax throughout the receptacle, so that a layer of hardened wax forms about the inner walls of the receptacle, and the wax used up by the thread is not replenished in a satisfactory manner by the supply of wax in the receptacle.

The primary object of the invention is to produce a thread waxing device of the character referred to, with an improved heating device which will insure the reduction of the wax to the proper consistency to permeate the thread where the thread passes through the receptacle, and the melting of the wax throughout the receptacle. With this object in view the invention contemplates the provision in a thread waxing device having a wax receptacle of a heating device extending into the receptacle and into the wax contained therein, and provided with an enlargement extending over and located adjacent to the base of the receptacle. By this provision the heat transmitting surface of the heating device is increased and

the wax at the base of the receptacle and above the enlargement is melted and flows in toward the heating device by which it is maintained in a thoroughly melted condition. Considerable heat is transmitted to the base of the receptacle and thereby conducted to the side walls of the receptacle, and prevents the formation of a layer of hardened wax about the inner wall of the receptacle. The enlargement in the heating device is preferably constructed so that it extends over substantially the entire area of the base of the receptacle.

In the accompanying drawings illustrating the invention in the best form at present known to the inventor, Figure 1 is a plan view of the thread waxing device; Fig. 2 is a front elevation of the thread waxing device with a portion of the receptacle broken away to show the interior of the receptacle; Fig. 3 is a section taken on the line 3—3 of Fig. 2; Fig. 4 is a side elevation of the device; Fig. 5 is an enlarged detail plan of a portion of the waxing device as illustrated in Fig. 1; Fig. 6 is a section taken on the line 6—6 of Fig. 5; and Fig. 7 is a section taken on the line 7—7 of Fig. 5.

The thread waxing device comprises a bracket 1 secured in any suitable manner to the frame of the sewing machine to which the waxing device is applied; said bracket being constructed to form a cover for the wax receptacle, as indicated at 2. The wax receptacle 3 is adjustably secured to the bracket 1 so that it may be raised and lowered with relation to the bracket. To this end a downwardly extending rod 4 is secured to the bracket 1, and the receptacle 3 is provided with a split clamp 5 for clamping the receptacle in position on the rod. The clamp is provided with an actuating bolt 6 having an enlarged head which may be manipulated by the operator to clamp the receptacle on the rod and to unclamp the receptacle when it is desired to lower it on the rod. A collar or washer 7 is attached to the lower end of the rod 4, and serves as a stop to prevent the receptacle from slipping off the rod when it is lowered.

In order to heat the wax in the receptacle a heating device is arranged so that it extends down into the receptacle and into the wax contained in the receptacle. This heating device is provided with an enlargement extending over and located adjacent the base.

of the receptacle, and devices for guiding the thread are preferably mounted so that the thread is guided through the receptacle in proximity to the heating device.

5 In the illustrated embodiment of the invention the heating device is constructed to contain a heating fluid, preferably steam or hot water.

10 In the construction illustrated the heating device comprises pipes 8 and 9 connected by a plate 10 attached to the lower ends of the pipes and provided with a chamber or passage connecting the pipes. The pipes 8 and 9 are clamped to the bracket 1 in a position such that the plate 10 is located near the base of the receptacle. The plate 10 forms an enlargement of the heating device, and is preferably constructed so that it overlies substantially the entire base of the receptacle.

15 In order to clamp the pipes 8 and 9 to the bracket 1, the bracket is provided with recesses to receive the pipes, as illustrated in Fig. 1, and the pipes are clamped against the bracket by means of a clamping plate 12 actuated by a clamping bolt 13. By this construction the heating device may be clamped in any desired position with relation to the receptacle and the plate 10 may be located at different distances from the base of the receptacle as desired.

20 The pipes 8 and 9 are connected with entrance and return pipes 14 and 15 for the heating fluid by means of nipples 16 threaded into the tubes 8 and 9 and interiorly threaded to receive the pipes 14 and 15. An angular plate 17 is secured to the side of the receptacle thereby forming a chamber for the reception of lumps of wax which are 25 placed therein to supply the receptacle, said plate being formed with a series of slots 18 through which the wax may flow when melted into the body of the receptacle. A thread truck 19 for guiding the thread 30 through the receptacle is carried by a supporting frame 20 which is clamped to the pipes 8 and 9.

35 The pipes 8 and 9, and the connecting plate 10, form a substantially U-shaped heating device, and by arranging the thread truck 19 as described, the thread is guided through the receptacle in proximity to the heating device. The plate 10 furnishes a large heating surface, and the heat from said plate rises through and raises the temperature of the wax throughout substantially the entire receptacle. Heat is transmitted by the plate 10 to the base of the receptacle, and thereby conducted to the walls thereof, preventing the hardening of the wax along the inner walls of the receptacle. The wax 40 above the plate and along the walls of the receptacle is melted and flows in toward the center of the receptacle where the heating device extends into the receptacle and where

the thread passes therethrough. The wax at the center of the receptacle and in proximity to the thread is readily reduced, to and maintained at the proper consistency by the heat transmitted by the heating device, and particularly by the pipes 8 and 9 thereof. By the provision for adjustment of the plate 10 with relation to the base of the receptacle, the heat transmitted to the base of the receptacle by said plate may be varied as de- 75 sired.

80 The stripping device for stripping the wax from the thread as the thread emerges from the receptacle is substantially the same in construction as the stripping device illustrated in the patent to Ashworth, No. 1,015,772, dated January 30, 1912. This stripping device comprises a compressible block 21 which is perforated to provide a passage for the thread, and which strips the wax from the thread as it passes therethrough. The block is compressed by a compressor 22 which is seated in a cap 23 threaded upon the upper end of a socket 24 mounted on the cover of the wax receptacle. To permit the ready removal of the block, a split sleeve 25 is provided to receive the block, and the sleeve is fitted into the socket 24. The socket is provided with a dovetailed rib 26 which is received in a dovetailed recess in the 95 cover of the wax pot, and the socket is held in the recess by means of a retaining screw 27.

100 Having explained the nature and object of the invention, and having specifically described the preferred embodiment thereof, what is claimed is:

1. A thread waxing device, having, in combination, a wax receptacle, a heating device having a body extending into the wax in the receptacle and comprising a heat conducting plate extending outwardly from the body of the heating device over and arranged adjacent the base of the receptacle, and means to guide the thread into and out of the receptacle above the plate. 105

2. A thread waxing device, having, in combination, a wax receptacle, a heating device extending centrally into the receptacle and into the wax in the receptacle and comprising a heat conducting plate arranged adjacent and extending outwardly toward the side walls of the receptacle over the base of the receptacle, and means to guide the thread into and out of the receptacle. 115

3. A thread waxing device, having, in combination, a wax receptacle, a heating device extending downwardly into wax in the receptacle and comprising a heat conducting plate extending over and arranged near the base of the receptacle, and means for guiding the thread into and out of the receptacle in proximity to the heating device and above the plate. 120

4. A thread waxing device, having, in 125

- combination, a wax receptacle, a substantially U-shaped heating device for containing the heating fluid extending within the receptacle and comprising entrance and re-
turn pipes for the heating fluid, a member
extending over and arranged adjacent the
base of the receptacle and provided with a
passage connecting said pipes, and means
to conduct the thread into and out of the
receptacle in proximity to the heating de-
vice.
5. A thread waxing device, having, in
combination, a wax receptacle, a substantially
U-shaped heating device extending
centrally into the receptacle and partially
immersed in the wax contained in the recep-
tacle and comprising a heat conducting
plate extending outwardly from the body of
the heating device over and arranged adjacent
the base of the receptacle, and means to 20
conduct the thread into and out of the recep-
tacle in proximity to the heating device.
6. A thread waxing device, having, in
combination, a wax receptacle, a heating de-
vice extending into the wax in the receptacle 25
and provided with an enlargement extending
over and arranged adjacent the base of the
receptacle, provision for adjusting the heat-
ing device to locate the enlargement at dif-
ferent distances from the base of the recep-
tacle, and means to guide the thread through
the receptacle.
